UNITED STATES PATENT OFFICE.

WEBB L. SMITH, OF SAN FRANCISCO, CALIFORNIA.

ELECTRICAL PLUG.

1,329,555.

Specification of Letters Patent.

Patented Feb. 3, 1920.

Application filed August 30, 1918. Serial No. 252,020.

To all whom it may concern:

Be it known that I, WEBB L. SMITH, a citizen of the United States, residing at the city and county of San Francisco and State of California, have invented new and useful Improvements in Electrical Plugs, of which the following is a specification.

This invention relates to an electrical plug, and particularly pertains to a plug adapted to be used with extension cords for domestic purposes.

One of the most common objections to electrical plugs used in connection with irons, electric cooking utensils and other devices of a portable nature has been that the wire and plug are bound against twisting movement, and it is well nigh impossible to handle a portable electric device without twisting the cord. At times it often occurs that the wires are broken. It is the principal object of this invention to provide an electrical plug which will insure constant contact between the various conductors, and, at the same time will allow the cord to rotate and twist as desired without being held against movement of the plug.

The present invention contemplates the use of an outer cap which is detachably positioned upon a threaded sleeve adapted to combine with the cap to hold the porcelain body member in place. This last named member is so designed as to receive the connections from the extension wire and to properly contact them with the socket into which the sleeve is screwed, at the same time allowing the porcelain and the wires to rotate within the sleeve without interruption of the passage of current throughout.

The invention is illustrated by way of example in the accompanying drawings in which—

Figure 1 is a view in side elevation disclosing the completely assembled plug and a portion of the extension wire carried thereby.

Fig. 2 is a view in longitudinal section and elevation illustrating the various vital elements of the plug and their relation to each other, and further indicating by dotted lines a socket into which the plug may be positioned.

Referring more particularly to the drawings, 10 indicates a cap cylindrical in section and having an end through which a wire opening 11 is formed. The cylindrical portion of the cap is provided with an annular

shoulder 12 at which point a screw thread is formed to extend outwardly to the opened cap end. This thread and shoulder are adapted to receive a metallic sleeve 13 preferably made of pressed metal as commonly designed. Due to the fact that the cap is made of dielectric material, the sleeve will be threaded therefrom and will act to secure a porcelain body member 14 in position between an outer flange of the sleeve and the opposite end of the cap. This porcelain member has an enlarged cylindrical body portion substantially conforming to the inner diameter of the sleeve and a reduced cylindrical body portion extending outwardly through an opening in the end of the sleeve.

A wire passageway 15 extends from the end of the body portion and terminates at the shoulder thereof. A second passageway 16 extends entirely through the body portion from one end to the other and terminates at the outer reduced face thereof. This last named passageway receives an electric conductor 17 which is fastened on the end of the plug by a combined binding and contact screw 18. The passageway 15 receives a conductor 19 which extends outwardly and engages a metallic contact ring 20. This ring circumscribes the reduced portion of the porcelain member and rests upon the shoulder formed by the enlarged portion of this member. The ring is furthermore held in position on this shoulder by the end flange of the sleeve 13 and is thus in continuous sliding contact therewith.

Due to the design of the device the sleeve 13 will strike the shoulder upon the cap to hold its end flange in spaced relation to the shoulder on the porcelain and to properly clamp the ring between the shoulder and the flange without binding the porcelain member, and thus permitting it to rotate within the sleeve and the cap.

In operation the device is assembled by first securing the wires 17 and 19 in fixed relation to the screw 18 and the ring 20, respectively. When this has been done the sleeve is positioned over the shoulder portion of the cylinder and thereafter the cap is slipped over the sleeve and tightened. In this assembled position the plug may be inserted into a socket and screwed into place by the threads upon the sleeve. When located properly within the socket the sleeve and cap will be held against movement rela-

tive thereto, and the socket and wires may be turned as desired. It will thus be seen that an electrical plug is provided which is composed of very few parts, easily formed, 5 and readily assembled, thus insuring that an unskilled person may repair the plug should contacts become broken.

It will further be seen that when in operation the extension cable will be held in a 10 manner to permit it to rotate without twisting and without the possibility of breakage.

While I have shown the preferred form of my electric plug as now known to me, it will be understood that various changes in the 15 construction, combination and arrangements of parts may be made by those skilled in the art without departing from the spirit of the invention as claimed.

Having thus described my invention, what 20 I claim and desire to secure by Letters Patent is:

1. An electrical connecting plug, including a body member having a reduced outer end forming a shoulder with the inner end, 25 a hollow cap member into which the larger end of the body is insertable, said cap having an annular interior shoulder, a spirally threaded contact member adapted to screw into co-acting threads in the cap, to lock 30 against the interior shoulder, said member having an inturned flange, and a contact ring on the body shoulder with which said flange turnably engages.
2. An electrical plug including a cylindri-

cal body member formed of dielectric material and having an outer part of reduced diameter to provide a shoulder, wires in said body member, a terminal at the end of the body member for one of the conducting wires, a terminal ring resting upon the 40 shoulder of the body member and adapted to be engaged by the opposite wire, a threaded sleeve fitting over the enlarged portion of the body member and turnable to be in continuous contact with said terminal ring, and 45 a cap engaged and turnable with the plug and with relation to the body member.

3. An electrical plug comprising a dielectric body member, a contact sleeve loosely inclosing said body and having an inturned 50 flange turnably engaging said body and forming a continuous electric contact, conducting wires, one of which contacts with the sleeve, and the other passes through the body, and a cap through which both wires 55 pass, said cap having a spiral thread and an interior shoulder against which the contact sleeve is immovably locked, and a conducting ring in sliding contact with the flange of the sleeve.

In testimony whereof I have hereunto set my hand in the presence of two subscribing witnesses.

WEBB L. SMITH.
